Application March 12, 1942, Serial No. 434,371

8 Claims.

(Cl. 2—68)

This invention relates to articles of apparel of the type having a flexible rib for sealing the interior of the article to prevent seepage of a fluid therein, and has particular reference to a novel article of apparel having a combination of ribs one of which is controlled by the action of the other rib or ribs so that its effectiveness in preventing seepage of fluids into the article is greatly increased. The new article is of simple construction, is comfortable to the wearer and can be manufactured at low cost.

For illustrative purposes, the invention will be described and illustrated in the form of a bathing cap, although it will be understood that it may take other forms as well.

Bathing caps as commonly made comprise a cap body having on the inside an encircling rib which presses against the skin of the wearer to prevent leakage of water into the cap under the edge. The encircling rib may take various forms, and in some caps it is designed to provide the greatest sealing effect when it is upset or deflected laterally by its pressure against the skin. In my Patent No. 2,206,402, granted July 2, 1940, I have disclosed a means for controlling the deflection of the encircling rib automatically under the pressure of the skin, the deflecting means comprising an off-center edge on the rib which is initially engaged by the skin to deflect the rib in the direction in which the edge is off-center. Because of this controlled deflection of the rib, it automatically conforms itself to the contour of the wearer's head, since the amount of its deflection is determined by the pressure on its end portion which, in turn, depends on the contour of the head. In other caps, the encircling rib may be designed to provide the greatest sealing effect when it remains substantially straight, and in caps of this form the rib should be controlled by stabilizing it in some manner to prevent it from upsetting under the pressure of the skin.

One feature of the present invention resides in the provision of a novel means by which the position of the encircling rib under the pressure of the skin against it may be controlled accurately without the use of an off-center edge on the rib. A bathing cap made in accordance with my invention comprises a flexible rib on the inside of the cap body extending generally parallel to the margin of the opening, and a second rib on the outside of the cap body extending generally parallel to the first rib but offset laterally therefrom. I have found that with this construction, when the cap is stretched on the head of

the wearer, each of the ribs acts to force the other rib laterally away from it due to the tension applied to the edge portion of the cap and the resulting pressure between the inner rib and the head. Thus, the rib on the inside of the cap is initially upset in a predetermined direction by the pressure of the skin against it, so that by providing the rib with a free end portion of appropriate form, the desired sealing action is obtained. It will be apparent that the new cap may be made reversible, because when it is turned inside out, the rib on the inside, formerly on the outside, is deflected laterally by the action of the other rib under the tension in the edge portion of the cap.

In bathing caps having encircling ribs of certain forms, it may be desirable to stabilize the rib under the pressure of the skin against it to prevent upsetting of the rib. In accordance with my invention, the encircling rib may be stabilized by employing on the outside of the cap body, in addition to the first outer rib, a second outer rib generally parallel thereto but on the opposite side of the encircling rib. When the cap is stretched on the head, one of the outer ribs acts to deflect the encircling rib upwardly, while the other outer rib acts to deflect the encircling rib downwardly. As a result, the action on the encircling rib of each of the outer ribs tends to counteract that of the other outer rib and cause the encircling rib to remain generally in its initial position without substantial deflection.

If desired, the inside of the cap body may be provided with two or more ribs extending in generally parallel spaced relation along the edge portion of the cap, and these ribs may be controlled by one or more ribs extending generally parallel thereto on the outside of the edge portion. By employing a single outer rib between the two inner ribs, the stretching of the cap on the head causes the inner ribs to be deflected away from each other so that they diverge under the pressure of the head against them. If it is desired to upset the inner ribs toward each other when the cap is applied to the head, a pair of outer ribs may be provided, one above and the other below the inner ribs. In caps having a plurality of encircling ribs on the inside, one of these ribs may be stabilized while the other is upset in a predetermined direction, by employing a pair of ribs on the outside of the cap body, one between the inner ribs and the other above or below the inner ribs.

The new bathing cap is of simple construction and may be made at low cost, since the ribs may

be molded on the cap body. By properly determining the relative positions of the inner and outer ribs, the action of the inner rib due to stretching of the edge portion of the cap may be accurately controlled, whereby the inner rib assumes the position in which it is designed to provide the desired sealing effect. When the cap is of the reversible type, each rib serves to determine the position of the sealing rib or ribs or acts itself as a sealing rib when the cap is reversed.

For a better understanding of the invention reference may be had to the accompanying drawing, in which

Fig. 1 is a side view of one form of a bathing cap made in accordance with the invention, with part of the cap broken away;

Fig. 2 is an enlarged cross sectional view of the ribs shown in Fig. 1;

Fig. 3 is a view similar to Fig. 2 illustrating the action of the ribs when the cap is applied to the head;

Figs. 4 and 5 are views similar to Figs. 2 and 3, respectively, showing the ribs when the cap is reversed;

Fig. 6 is a cross sectional view of part of a modified form of the cap, showing the ribs;

Fig. 7 is a view similar to Fig. 6 illustrating the action of the ribs when the cap is applied to the head;

Figs. 8 and 9 are views similar to Figs. 6 and 7, respectively, showing the position of the ribs when the cap is reversed;

Fig. 10 is a cross-sectional view of part of still another form of the cap showing the ribs;

Fig. 11 is a view similar to Fig. 10 showing the action of the ribs when the cap is applied to the head;

Fig. 12 is a cross-sectional view illustrating the form of the invention in which there is only one rib on the inside of the cap and one on the outside; and

Fig. 13 is a view similar to Fig. 12 showing the action of the ribs when the cap is applied to the head.

The bathing cap, as shown, comprises an elastic cap body 12 of any desired shape, which may be made of rubber or other water-proof material having the desired elasticity. On the inside of the cap body near the edge 13 are a pair of encircling ribs 14 and 15. The ribs may be made of the same material as the cap body and are preferably of greater depth along the side portions of the cap than at the front and back, as is common in apparel of this type. An encircling rib 16 on the outside of the cap body extends generally parallel to the inner ribs 14 and 15 but is offset laterally therefrom so that it lies above the lower rib 15 and below the upper rib 14, the rib 16 being preferably equi-distant from the inner ribs. The outer rib may be of the same form as the inner ribs, and all of the ribs may be made integral with the cap body, as by molding them on the body in the same molding operation by which the body itself is formed.

The free end portions of the inner ribs 14 and 15 may take any desired form, but, as shown, they are provided with longitudinal fins 14a and 15a, respectively, each of which is offset from the centerline of the rib on the side adjacent the other rib. The outer rib 16 may be provided with a rounded, symmetrical end portion.

In applying the cap to the head 17 of the wearer, the portion adjacent the edge 13 is stretched to enable the cap to be drawn over the

head, and due to the resulting tension in the edge portion and the pressure of the inner ribs 14 and 15 against the head, the inner ribs are deflected away from each other. The pressure of the head against the inner ribs deflects the ribs apart until they reach a position of stability determined by their resistance to upsetting and the tension in the edge portion, as shown in Fig. 3. In the final position of the inner ribs, the fins 14a and 15a contact the skin and form recesses with the adjacent end portions of the ribs. The pressure to which the inner ribs are subjected due to the tension in the cap tends to force the air from these recesses and create a suction therein, so that the ribs are more effective to prevent seepage of water into the cap body under the edge 13. Also, the deflection of the inner ribs away from each other by the action of the outer rib and the pressure against the head tends to expel air from the space between these ribs and create a suction in the space, which provides a better sealing action.

While the inner ribs may be made sufficiently stiff to prevent them from being completely upset under the pressure against them, it may be desirable in some instances to provide cross ribs 18 between the inner ribs so as to limit positively their deflection and insure proper contact of the fins 14a and 15a with the skin. The pressure between the head and the inner ribs upsets these ribs away from each other an amount dependent on the pressure along the ribs which, in turn, depends on the contour of the head. Accordingly, the ribs by their deflection automatically accommodate themselves to the shape of the head.

I have found that with the new construction, the outer rib 16 acts to control the deflection of the inner ribs 14 and 15 so that the inner ribs are always deflected away from each other in the normal application of the cap to the head. The controlling action of the outer rib 16 is possibly due to the fact that it provides between the inner ribs a region of increased resistance to bending and longitudinal stretching, with the result that when the cap is stretched on the head the inner ribs 14 and 15 act to force the adjacent parts of the edge portion away from the head while the rib 16 causes the part of the cap intermediate the inner ribs to seek the head. Accordingly, the edge portion of the cap assumes the wave-like form shown in Fig. 3, in which the surfaces of the cap body adjacent the inner ribs are tilted outwardly from the head, and since the inner ribs 14 and 15 tend to remain normal to the adjacent surfaces of the cap body, the tilting of these surfaces causes the inner ribs to be deflected away from each other, the deflection of the ribs being accentuated by the pressure of the ribs against the head, as previously described.

If desired, the cap may be turned inside out, as shown in Fig. 4, so that the single rib 16 acts as a sealing means to prevent seepage of water into the cap body. When the cap is reversed in this manner and the edge portion stretched incident to applying the cap to the head, the outer ribs 14 and 15 act to stabilize the inner rib 16 and resist or prevent upsetting thereof by the pressure of the head against it. More particularly, the upper rib 14, due to the tension in the edge portion of the cap, acts to deflect the inner rib 16 downwardly, while the lower rib 15 acts to deflect the inner rib upwardly, so that the action of each of the outer ribs is coun-

ter-acted by the other and the inner rib is held firmly in its normal position, as shown in Fig. 5. The end portion of rib 16 is pressed against the head, whereby an effective sealing action is obtained.

The bathing cap shown in Figs. 6 to 9, inclusive, comprises an elastic cap body 20 having a pair of encircling ribs 21 and 22 on the inside adjacent the edge. On the outside of the cap body are two similar ribs 23 and 24 generally parallel to the inner ribs but staggered with respect thereto. That is, the outer rib 24 is disposed above the inner rib 21 and below the inner rib 22 and preferably substantially equi-distant therefrom, while the outer rib 23 is disposed above the inner rib 22 so that the latter is substantially equi-distant from the outer ribs.

When the cap body 20 is applied to the head of the wearer, the lower rib on the outside of the body acts under the tension in the edge portion to deflect the inner ribs 21 and 22 away from each other. However, the outer rib 23 counteracts the effect of the outer rib 24 on the inner rib 22, and, therefore, the latter is stabilized and assumes substantially its initial position, as shown in Fig. 7. The inner rib 21, however, is deflected downwardly by the action of the adjacent outer rib 24. Accordingly, a double seal is provided along the edge portion of the cap by the downwardly deflected rib 21 and the stabilized rib 22. Due to the deflection of the inner rib 21 away from the inner rib 22, the pressure on these ribs resulting from the tension in the cap tends to expel air from the space between the inner ribs and create a suction in the space, which aids in resisting seepage of water into the interior of the cap. Since the suction effect is obtained without deflection of the inner rib 22, the pressure against the end portion of rib 22 is greater, so that this rib provides a more positive seal. If desired, the inner rib 21 may be provided on its free end portion with a fin (not shown) which is off-set from the centerline of the rib on the side adjacent the upper rib 22, so that when the rib 21 is deflected the fin is forced into contact with the skin and forms a recess with the adjacent end portion of the rib, as described in connection with the cap shown in Figs. 1 to 5, inclusive. It will be observed that any water passing under the edge of the cap body 20 will strike against the deflected lower rib 21 and act to force the rib upwardly and thereby increase the pressure between its end portion and the head of the wearer.

When the cap 20 is turned inside out or reversed, the ribs 23 and 24 act to prevent seepage of water into the cap body. That is, when the cap is reversed and applied to the head 17, the edge portion of the cap body is subjected to tension with the result that the rib 22, now on the outside, acts to force the skin-contacting ribs 23 and 24 away from each other. However, the outer rib 21 counter-acts the effect of rib 22 on the inner rib 24, and, therefore, the latter is stabilized and held against any substantial deflection, as shown in Fig. 9. The inner rib 23, which is deflected upwardly by rib 22, may be provided with a fin (not shown) disposed in such a position that it is forced into contact with the skin when the rib is deflected and thereby forms with the rib a suction recess, as previously described. The upward deflection of the inner rib 23 tends to form a suction in the space between the inner ribs, so that a more effective seal is obtained.

The bathing cap shown in Figs. 10 and 11 comprises a cap body 26 having a pair of encircling

ribs 27 and 28 on the inside extending in generally parallel spaced relation adjacent the edge. Encircling ribs 29 and 30 are disposed on the outside of the cap body, one above the inner rib 27 and the other below the inner rib 28. With this construction, when the cap is applied to the head and the edge portion is subjected to tension, the outer ribs act to force the inner ribs toward each other, as shown in Fig. 11. It will be apparent that when the cap is reversed so that the ribs 29 and 30 engage the head, the ribs 27 and 28 act to force the skin-contacting ribs away from each other. If desired, the ribs 27, 28, 29 and 30 may be provided with fins 27a, 28a, 29a and 30a, respectively, located on the end portions in off-center relation, so that when either set of ribs is disposed on the inside of the cap body the corresponding fins are forced into contact with the skin by deflection of the ribs, whereby a better sealing action is obtained.

Fig. 12 shows a bathing cap 31 having a single flexible rib 32 on the inside of the cap and a single rib 33 on its outside. The outside rib 33 extends generally parallel to the inside rib and is laterally off-set therefrom. When such a cap is applied to the head the inside rib is deflected downwardly and the outside rib is deflected upwardly as shown in Fig. 13.

The new bathing cap, being reversible, may be made of contrasting colors on opposite sides so that the wearer has the advantage of two different decorative effects. Since the rib on each side of the cap always coacts with that on the other side to control its position, an effective seal is provided regardless of which side of the cap is selected for the outside.

I claim:

1. An article of apparel comprising a hollow body having an opening therein and an elastic edge portion adjacent the opening, a flexible rib on the inside of the elastic portion normally projecting substantially at right angles to the surface thereof and extending generally parallel to the margin of the opening, and a flexible rib on the outside of the elastic portion normally projecting substantially at right angles to the surface thereof and extending generally parallel to said first rib and offset laterally therefrom, one of said ribs acting to cause lateral deflection of the other rib away from it when the elastic portion is stretched on the wearer.

2. An article of apparel comprising a hollow body having an opening therein and an elastic edge portion adjacent the opening, an elastic rib on one side of the elastic portion extending generally parallel to the margin of the opening, and a pair of flexible ribs on the opposite side of the elastic portion extending generally parallel to the first rib, one of said last ribs being offset laterally from the first rib on one side thereof and the other of said last ribs being offset laterally from the first rib on the other side thereof.

3. An article of apparel comprising a hollow body having an opening therein and an elastic edge portion adjacent the opening, a flexible rib on the inside of the elastic portion normally projecting substantially at right angles to the surface thereof and extending generally parallel to the margin of the opening, a flexible rib on the outside of the elastic portion normally projecting substantially at right angles to the surface thereof and extending generally parallel to said first rib and offset laterally therefrom, one of said ribs acting to cause deflection of the other rib away from it when the elastic portion is stretched on

the wearer, and a sealing edge disposed on the free end portion of the first rib on one side of the center line thereof in position to contact the skin of the wearer when the first rib is deflected.

4. A bathing cap comprising a hollow cap body having an elastic edge portion adjacent the opening, an elastic rib on the outside of the elastic edge portion extending generally parallel to the margin of the opening, and a pair of flexible ribs on the inside of the elastic edge portion extending generally parallel to the first rib, one of said inner ribs being offset above the outer rib and the other of said inner ribs being offset below the outer rib, the outer rib acting to deflect the inner ribs away from each other to create a suction effect between the inner ribs when the elastic portion is stretched on the head.

5. An article of apparel comprising a hollow body having an opening therein and an elastic edge portion adjacent the opening, a pair of flexible ribs on the inside of the elastic portion extending generally parallel to the margin of the opening, and a pair of elastic ribs on the outside of the elastic portion extending generally parallel to said first ribs and staggered with respect thereto.

6. An article of apparel comprising a hollow body having an opening therein and an elastic edge portion adjacent the opening, a pair of flexible ribs on one side of the elastic portion extending generally parallel to the margin of the opening in spaced relation, and a pair of elastic ribs on the other side of the elastic portion extending

generally parallel to the first ribs in spaced relation and offset laterally therefrom, one of said last ribs being disposed above the first ribs and the other of said last ribs being disposed below the first ribs.

7. A reversible bathing cap comprising a hollow cap body having an elastic edge portion adjacent the opening, a pair of flexible ribs on the inside of the cap body extending generally parallel to the margin of the opening in spaced relation, and a pair of elastic ribs on the outside of the elastic portion extending generally parallel to the first ribs in spaced relation and offset laterally therefrom, one of the outer ribs being disposed above the inner ribs and the other outer rib being disposed below the inner ribs, the outer ribs acting to force the inner ribs toward each other when the elastic portion is stretched on the head.

8. An article of apparel comprising a hollow body having an opening therein and an elastic edge portion adjacent the opening, a flexible rib on the inside of the elastic portion normally projecting substantially at right angles to the surface thereof and extending generally parallel to the margin of the opening, and an elastic rib on the outside of the elastic portion extending generally parallel to said first rib and offset laterally therefrom, said last named rib acting to cause lateral deflection of the first named rib away from it when the elastic portion is stretched on the wearer.

THOMAS J. HOWLAND.
